METAL-FACED CABINET FOR REFRIGERATORS AND OTHER PURPOSES

Application filed January 7, 1926. Serial No. 79,713.

The present invention has for its object to produce a metal-sheathed cabinet or shell that shall be strong, rigid and not liable to distortion through warping or swelling, which may be made of light sheet metal and wooden backing or frame members of cheap or low grade material, and which may be made in a knocked-down condition and be assembled easily and at very small expense 5 at the place where it is to be adapted for its ultimate use.

In carrying out our invention, we form a simple wooden frame having the dimensions of the front of the cabinet, and cover this 10 frame with sheet metal that is formed to fit over the outer face of the frame, over the outer side edges and over the inner side edges around the door opening or openings. The metal is glued to the frame under heavy pressure 15 while lying on a flat anvil, so that the sheathed frame has a perfectly flat outer face. The margins of the metal bounding the door opening or openings may afterwards be covered by portions of door stops placed around 20 such opening or openings to form abutments against which the door or doors may bear. Each door includes a flat core or body 25 sheathed on both faces with metal glued thereto under pressure to produce a flat panel, the metal extending around the edges of the core so as completely to enclose the core in metal. The core of the door is thus protected against 30 moisture and the door as a whole will be proof against warping when in use. The doors are made hollow and are adapted to 35 be filled with suitable heat-insulating material. The side and rear walls and the top and bottom of the cabinet are in the form of flat panels made of stock sheathed on both 40 sides with metal glued thereto. The panels are suitably shaped so that they may be assembled with the front to form a strong rigid shell or cabinet requiring no other frame work or bracing. All sheathing is securely 45 glued to the underlying body material whether it be a frame member or simply a panel, and the marginal portions of the sheathing are extended or at any rate so located that they will be covered by a molding 50 or other part. Aside from the glue, no other

fastening means, unless it be dowel pins or mortising, except nails of various sizes, need be employed, unless other fastening means are desired. The final assembly of the parts to form the cabinet is effected by nailing the 55 various elements together, many small nails, placed fairly close together, being employed. Since there is no framing or bracing to give shape to the structure, aside from the wall elements themselves, there will be no distortion of the same when the cabinet is subjected 60 to vibrations as it is when housing or supporting a motor or when standing on a floor that supports or is subjected to the vibrations of a motor, engine or the like. The 65 frame forming the front may be built up to any desired thickness by nailing or otherwise securing boards or strips to the inner side thereof.

Our improved construction is particularly applicable for use as the outer shell of a refrigerator, because the doors may fit tightly without exposing the metal sheathing within the door openings or on the door to the interior of the refrigerator when the 70 doors are closed; and because there cannot be sufficient distortion of the core parts whereby the seal is effected, when a door is closed, to cause cracks to appear between the door and the abutments therefor. In manufacturing a refrigerator, an inner shell, between which and the outer shell the insulation is confined, may readily be assembled with its insulation in a condition to be 75 clamped securely in the outer shell in assembling the latter.

The various features of novelty whereby our invention is characterized will herein-after be pointed out with particularity in the claims; but, for a full understanding of our invention and of its objects and advantages, reference may be had to the following detailed description taken in connection with the accompanying drawings, wherein:

Figure 1 is a perspective view of a completed cabinet, the hinges and fastenings of the doors being omitted; Fig. 2 is a front elevation of the wooden frame for the front of the cabinet; Fig. 3 is a view similar to Fig. 2, showing the frame after the metal sheath- 95 100

ing has been applied thereto; Fig. 4 is a view similar to Fig. 3, showing the frame after the door stops and thickening pieces have been applied; Fig. 5 is a vertical central section, on an enlarged scale, on line 5—5 of Fig. 4; Fig. 6 is a section, on an enlarged scale, on line 6—6 of Fig. 4; Fig. 7 is a section on line 7—7 of Fig. 4; Fig. 8 is a top plan view of the upper rear cleat and fragments of the two upper side cleats; Fig. 9 is a section through a fragment of one of the metal sheathed panels for forming the sides and back, illustrating the manner in which the panel is prepared prior to bending it to form a sharp corner; Fig. 10 is a horizontal section through the rear portion of the cabinet showing a fragment thereof; Fig. 11 is a vertical section through the cabinet on a plane extending at right angles to the front and rear walls of the cabinet; Figs. 12 and 13 are respectively a top plan view and a side elevation of one of the legs of the cabinet; Fig. 14 is a section through the front of the cabinet at the bottom, showing the manner of attachment of one of the legs; and Fig. 15 is a section through the top front corner of the cabinet, showing a slight modification.

In the drawings we have illustrated a construction that may be advantageously employed in the manufacture of refrigerators having an upper door and a lower door and, for the sake of brevity, the detailed description will be confined to this particular embodiment of the invention; although the invention is not limited to this particular use.

The foundation for the front wall of the cabinet is a rectangular wooden frame, shown in Fig. 2; the frame conveniently consisting of two upright side members 1 and 2 and cross pieces 3, 4 and 5. These several frame members may be of any desired size and of any desired material. Since they are to be metal sheathed, as hereinafter explained, they may be made of comparatively low grade wood.

As a matter of fact, the frame may be made of boards not over an inch thick, since added thickness may be built up on the inner side thereof if the purposes for which the cabinet is used require it. The cross pieces may be fastened to the uprights by means of dowel pins 6, best shown in Figs. 2 and 6. Nails 7 may be driven through the frame and through the ends of the dowel pins; thus producing a construction in which the parts may all be machine made and then be quickly assembled and securely fastened by the mere act of driving a number of small nails. After the frame has been assembled as shown in Fig. 2, it is faced with sheet metal overlying one face and flanged to cover the edges of the frame members. The metal is fastened to the wood by gluing it, preferably under heavy pressure. In the arrangement shown, there are sheet metal channels 9, 10 and 11 covering the cross bars 3, 4 and 5 respectively; the webs of these

channels being preferably extended across the adjacent portions of the side members of the frame and across the outer edges of the latter, thereby to serve as additional ties or fastening means between the cross members and the upright members. Other sheet metal channels 12, 12 are glued on the uprights.

The channel 11 is made wider than the frame member 5, so that the bottom flange 13 lies parallel with the bottom edge of this member but at a distance below the same equal to the thickness of the bottom panel to be hereinafter described, as shown in Fig. 5.

The metal face of the frame should show no joints and therefore, when the sheathing is made of separate pieces, as shown, they should overlap where they meet, to prevent the glue from interfering with successful soldering of the joints. The joints may therefore be made as shown in Fig. 7, wherein the ends 14 of the channels 12 are reduced in size to an amount equal to twice the thickness of the sheet metal from which the channels are made. Therefore the webs of the transverse channels, when lying upon these reduced ends of the upright channels are flush with the outer faces of the latter channels, and solder flowed into the joints will not come in contact with the underlying glue.

The next step in the production of the front of the cabinet is the attachment of the door stops. The door stops may be in the form of a wooden frame 15, somewhat longer and wider than the foundation frame and having openings adapted to register with but smaller than the door openings in the latter. When this auxiliary frame is secured to the rear face of the foundation frame, it projects beyond the top and side edges of the latter, forming with the same a cove or groove 16 extending across the top and down the sides of the foundation frame, and also projects into the door openings a sufficient distance to provide each door opening with a door stop at all four sides. It is desirable that the raw edges of the sheet metal extending into the door openings be concealed, and we therefore thicken that part of the auxiliary or door-stop frame over those areas which register with the main door openings, by forming thereon ribs or ledges 17 that enter the main door openings and slightly overlap the sheet metal flanges in the door openings.

In order to secure added strength and rigidity for the front of the cabinet, a third frame 18, of wooden boards or strips, may be fastened to the inner side of the door-stop frame. The outside width and height of this frame may be the same as the corresponding dimensions of the door-stop frame; but the openings therein being smaller than those in the door-stop frame, so that door openings decrease in size at the door-stop frame and again at the innermost frame.

Each of the doors is made of a simple rec-

tangular frame 19, of wood, that approximately fits its door opening, that is the main portion of the door opening bounded by the metal sheathed frame elements; the inner portion of this frame being smaller, as indicated at 20, to permit it to pass through the openings in the two inner frames. At what may be termed the base of the reduced portion of the frame on which the door is built is a gasket 21; this gasket being compressed between the door stops and the door when the door is closed. The outer face of each door is formed of a suitable panel 22 sheathed with sheet metal 23 on both sides, the metal being securely glued to the body of the panel. The metal sheathings are wider and longer than the body of the panel so as to permit them to be bent over the edges of the body portion of the panel and overlapped, as indicated at 24. This panel is fastened to the frame 19 by means of nails 25 driven through the flange or enlarged portion of this frame and into the panel while the latter is supported on an anvil or other suitable solid support, whereby the nails, when they strike the inner surface of the outer metal sheathing, will be deflected and become clinched. The inside of each door is formed of a metal or metal-sheathed panel 26 fastened in place by means of cleats 27 overlying the inner face of the panel and nailed through the panel to the frame 19. The door is therefore hollow and may be left with a mere insulating air space, or it may be filled with suitable insulating material. In any event, the door may be made by the manufacturer of the cabinet, with the inner panel detached, and thereupon the manufacturer of the refrigerator may place in the door the desired insulation and then attach the inner panel or wall.

Aside from the front frame, no other framing is required, since the panels, to be described, give the necessary strength and rigidity to the structure. The sides and back of the cabinet may be made of two metal sheathed panels, each of which covers one side and one-half of the back. A fragment of such a panel is shown in Fig. 9, in which 30 represents the body member and 31 the metal sheathing on the flat faces thereof. A V-shaped groove 32 is across each of these panels, through the body portion thereof, along the line where the panel is to be bent to form one of the rear corners. The sheathing along that edge which is to be at the front of the panel is extended beyond the body member, as indicated at 33, to form a lip or flange. This overhanging metal lip or flange is wider than the thickness of the panel as a whole so that when bent laterally across the edge of the panel it projects beyond the inner face of the latter and enters the cove 16 in the adjacent side post of the front frame when the panel is placed against said post. The top of the

cabinet consists of a panel 34 sheathed on both sides with metal, as indicated at 35. The metal sheathing on the outer face of this panel is made large enough to project beyond the body member at all four sides, so as to provide lips or flanges 36 as best shown in Fig. 11; those lips or flanges being wider than the thickness of the panel and being bent down past the edges of the panel so as to project below the same. It should be noted that flanges of the type just described are formed along the upper edges of the two panels that constitute the two side and the rear walls, these flanges being bent inwardly, as indicated at 37 in Fig. 11.

The bottom of the cabinet is formed of a simple panel 38 sheathed on both sides with sheet metal 39. This panel is adapted to enter the groove or trough between the bottom of the front frame and the flange 13 heretofore described, and best shown in Fig. 5; the flange being spaced apart from the bottom edge of the frame a distance equal to the thickness of the bottom panel. Consequently the front of the bottom panel is supported directly by the bottom flange of the metal sheathing on the front frame. The same kind of support is provided at the sides and rear of the bottom panel. To this end the outer sheathing on each of the panels adapted to form the side and rear walls of the cabinet is extended downwardly past the core or body of the panel and is bent inwardly along a line spaced apart from the bottom edge of the body or core a distance equal to the thickness of the bottom wall. There is thus formed a horizontal shelf 40 along the bottom edges of the side and rear walls of the cabinet, in the same plane as the flange or shelf 13 on the front frame, to support the bottom panel. When the parts are assembled, the bottom panel rests on these shelves and is engaged at its upper face with the bottom of the front frame and the bottom edges of the cores or bodies of the side and rear walls.

The members constituting the six walls of the cabinet are adapted to be fastened together by simple nailed joints. We therefore provide several nailing cleats for use in the corners where there is not already a backing into which nails may be driven. In the arrangement shown, there are four of these cleats, two in the upper side angles or corners and the others in the upper and lower rear angles or corners. The upper three cleats or nailing strips are shown in Fig. 8, in which 41 is the upper rear cleat and 42 and 43 are the two upper side cleats. These cleats are so shaped as to produce a cove 44 following their upper outer corners and form with the cove 16 at the top of the front frame a continuous groove or cove extending around the top of the cabinet. The top panel is laid on these cleats, with the flanges 36 at the sides and

- along the rear entered into the coves 44. Many small nails 45 are then driven through these flanges and into the cleats, firmly securing the cleats and the top panel together.
- 5 If desired, the cleats 42 and 43 may stop short of the front edge of the top panel, as shown in Fig. 11, so as to abut against the rear face of the front frame when the front flange 36 of this panel lies in the cove 16.
- 10 When the parts of the cabinet are to be assembled, the two panels that are to form the side and rear walls are laid edge to edge, with a vertical nailing strip 46 underlying the meeting edges, as shown in Fig. 10. A thin flat molding strip 47 is laid over the joint on the outside of the panels, and nails 48 are driven through this strip and the panels and into the cleat or nailing strip 46. The final nailing strip 49 is then nailed across the 20 united panels along the bottom of that portion that is to form the back wall of the cabinet. The top and bottom panels are then placed in proper relation to the front member and the united side and rear panels are 25 brought into proper relation to the rear edges of the top and bottom panels and the wings bent forwardly until they engage the sides of the front member with the flanges 33 lying in the vertical coves 16 in the front member.
- 30 During this assembly operation, the insulating material and the refrigerator lining, not shown, will have been brought into proper position with respect to the front, top and bottom. Then, after all the parts have been assembled, suitable clamps are applied, pressing all of the parts into their final positions, and the joints are nailed. Nails, all indicated by the reference character 45, are driven through the front flange 36 of the top panel 35 and into the front frame, through the top flanges 37 on the side and rear panels and into the top nailing cleats, and upwardly through the flanges 13 and 40 and the overlying bottom panel into the front frame and the rear nailing strip 49.
- 40 After the parts have been assembled, as just explained, suitable moldings or strips 50 are placed into the cove surrounding the top of the structure and also into the coves formed 45 in the two front vertical corners, these moldings or strips being fastened in place by means of nails 51 driven through the same and into the frame members against which they lie. It will be seen that these molding 55 elements not only serve to finish the corners that are ordinarily exposed, but they assist in securing the panels in place by reason of the fact that they clamp the flanges on the panels between the moldings and the inner 60 frame.
- 65 It will be seen that the entire outer surface of the cabinet, except the moldings, unless the latter be metal sheathed, is covered with sheet metal which has no edges exposed, even though it be made of a considerable number

of pieces. It will also be seen that all of the elements of the cabinet may be properly cut as a factory process and be shipped in a flat, knocked-down condition to a remote point, and that when the parts reach their destination they may be quickly assembled and secured together, to form a strong rugged cabinet, by simply placing the parts in proper relation to each other and driving numerous small closely spaced nails into the same.

70 Since the several factory-made parts are assembled by nailing them together, the rigidity of the structure depends on the nailed joints and a lack of stretching capacity in the panels. If one of the panels, say the top panel is pounded, or has a heavy pressure applied to its flat surface along an edge, the body portion thereof might be compressed to an extent which would leave a slackness in the sheathing where it turns the corner, possibly resulting in a looseness in the structure. Any such possibility may be avoided by flanging both of the sheathings into the coves. Such an arrangement is shown in Fig. 15 wherein, 60 is the body or core of the top panel, and 61 and 62 are the metal sheathings. The inner sheathing extends beyond the core and is flanged into the cove in the frame as indicated at 63; the outer sheathing being also bent down into the cove as indicated at 64. When the nails 51 are driven through these flanges and into the frame member, no displacement of the panel can take place without stretching the metal of the inner sheathing. Therefore, even through the core of the sheathing should be crushed, the structural rigidity of the shell or cabinet would not be impaired. Another advantage of this construction is that accurate assembly is made easier and more certain. When the panels are placed in position it is natural to pull them more or less. Such pulling might result in a slight crushing of the corner of the core over which the outer sheathing is bent and a slight displacement of the panel as a whole. After the two flanges of a double-sheathed panel have been nailed in place, however, no pull, short of one that will draw out the nails, will have any displacing effect on the panel as a whole.

75 90 95 100 105 110 115 120 125 130

Attention is called to the fact that we are able to produce a shell or cabinet in which the outer faces of the walls are substantially perfect plane surfaces, something that has not heretofore been possible in constructions much more costly. The metal sheathing is glued on the front frame under heavy pressure, with the web portions of the channels engaged with a true plane surface. Then, after the glue has set, the sheathing so ties the frame together that no distortion takes place and the character initially given to the outer face of the frame remains permanent. The gluing of the sheathing on the panels is effected in the same way so that the panels are

perfectly flat. The parts, being accurately cut before being assembled to form the cabinet, are not subjected to any stresses, during assembly, which would cause distortion. 5 Consequently the faces of the completed cabinet are perfectly flat.

It will therefore be seen that we have produced a construction that can be made at a low labor cost, of inferior wooden framing, 10 if desired, that may be shipped in a knocked-down condition and be easily and quickly assembled, and which, when assembled will be an attractive, strong and rigid cabinet with perfectly flat metal faces. Furthermore, 15 while our improved cabinet may be used for various purposes, it is particularly applicable to refrigerators, because any desired interior construction can readily be applied thereto and because of the improved door openings 20 and closures therefor which permit the use of tightly fitting doors and, if desired doors that lie flush with the front face of the cabinet.

The structure heretofore described is a cabinet without legs. If supporting legs are desired, these may conveniently be made as separate elements secured to the bottom panel and forming with them a single unit. A suitable form of leg is illustrated in Figs. 12-14. Each leg is made of two pieces of sheet metal 30 bent into angle shape and welded together to form a box-like structure open at both ends. These two pieces are indicated at 70 and 71. The upper margins of the outer member, 70, are bent inwardly to form flanges 72, while 35 the upper marginal portions of the inner members 71 are bent outwardly to form flanges 73 whose upper faces lie in a plane elevated above the plane of the tops of the flanges 72 a distance equal to the thickness of 40 the metal sheathing on the walls of the cabinet. Therefore, when such a leg is set under a corner of the cabinet, the flanges or shelves 13, 45 rest on the flanges 72 and the body portion of the bottom sheathing for the bottom wall of the cabinet rests on the flanges 73, giving a firm support on all parts of the leg.

The legs may conveniently be bolted to the bottom panel. To this end we have welded in the top of each leg a transverse wall 74 provided with a bolt hole 75. A bolt 76 may be passed through the hole in the plate or wall 74 and through the bottom panel, as shown in Fig. 14. The front frame may be cut away on the under side, as indicated at 77, to provide spaces to receive the heads of the bolts that secure the front legs. The rear lower nailing strip may be similarly treated at the point where the rear legs are located.

While we have illustrated and described 60 with particularity only a single preferred form of our invention, with a simple modification, we do not desire to be limited to the exact structural details thus illustrated and describe; but intend to cover all forms and 65 arrangements which come within the defini-

tions of the invention constituting the appended claims.

We claim:

1. A preformed article of manufacture adapted to form the front wall of a refrigerator or the like comprising a wooden frame and a metal sheathing glued over the front face of the frame the sheathing being flanged over the outer edges and into the frame opening. 70

2. A preformed article of manufacture adapted to form the front wall of a refrigerator or the like, comprising a rectangular wooden frame having a cross piece between the top and bottom, and a sheathing of sheet metal glued upon the front face of the frame, the edges of the sheathing being flanged over the outer edges of the frame and also over the edges bounding the frame openings. 75 80

In testimony whereof, we sign this specification. 85
